DISPLAY DEVICE

**Nathan Joseph Leigh, Great Neck, N. Y., assignor
to Einson-Freeman Co., Inc., Long Island City,
N. Y., a corporation of Delaware**

Application May 5, 1936, Serial No. 77,905

4 Claims. (Cl. 40—126)

My present invention relates generally to display devices.

5 While the present invention is intended primarily for use with the cardboard type of knock-down device, which is adapted to be displayed in a store window or on a counter or the like, nevertheless it will be understood that certain phases of the invention are not restricted to a display device of this particular character.

An object of the invention is to provide an improved and highly attractive display structure by means of which a stream of flowing liquid may be effectively depicted. My invention is thus of particular applicability to displays advertising paints, oils, and the like, although it will be understood that the novel features of the present device are equally applicable to any display in which it is desired to depict a stream of flowing liquid.

20 By way of example, I have herein illustrated
and shall hereinafter describe a display device
of the present character by means of which a
brand of paint is advertised. Paint is typical of
the viscous liquids whose depiction, in the form
25 of a flowing stream or streams, may be strik-
ingly effected by the present invention.

30 My invention is predicated upon the discovery that a concave blank of cardboard or the like, having a colored surface of high lustre, preferably composed of colored metallic foil, is peculiarly effective in producing a variegated sheen similar to that which is produced by a flowing stream of colored viscous liquid, such as paint or oil. My present invention enhances this effect by positioning a concave member of this character behind an opening in a panel, the opening having the contour and configuration of a flowing stream. The effect is enhanced still further by providing on the panel a depiction of the source of the flowing stream.

40 Another feature of my invention lies in providing a panel portion which projects into the opening and hence apparently into the path of the flowing stream of liquid. On this portion 45 I depict something which is apparently subjected to the action of the liquid.

I achieve the foregoing objects, and such other objects as may hereinafter appear or be pointed out, in the manner illustratively exemplified in the accompanying drawing, wherein—

Figure 1 is a front view of a display device embodying the features of the present invention;

Figure 2 is a cross-sectional view taken substantially along the line 2—2 of Figure 1;

55 Figure 3 is a fragmentary cross-sectional view

taken substantially along the line 3-3 of Figure 1;

Figure 4 is a fragmentary cross-sectional view taken substantially along the line 4—4 of Figure 1; and

Figure 5 is a rear view of the display device with a portion omitted for the sake of clearness.

A front panel 10 having any suitable configuration is adapted to be supported in substantially upright position by means of any usual type of rear prop 11. On the front face of the panel any suitable advertising indicia may be provided, and, among other things, the panel bears a depiction of the source of a stream of flowing liquid. In the illustrated embodiment, the panel has portions 12 and 13 which depict cans of paint tipped so as to permit the contents to pour out of them. In the proper relationship to these depictions the panel is provided with the openings 14 and 15, each of which has approximately the contour of the stream of liquid which would flow from the cans 12 and 13. In each case, so far as the present illustrative example is concerned, the contour of the opening is that of a falling stream of gradually increasing width. 15 20 25

In accordance with my present invention, a blank of cardboard or the like, designated by the reference numeral 16, is arranged behind the opening 14 and is flexed into conformity with the surface of a cone whose apex is directed upwardly. One edge of the blank 16 is permanently hinged, by a connecting strip 17, to the rear face of the panel 10 adjacent to one longitudinal edge of the opening 14. The opposite edge of the blank 16 is removably braced beneath an abutment strip 18 which is adhesively secured to the back of the panel 10 adjacent to the opposite edge of the opening 14. The blank 16 is so shaped, and the strips 17 and 18 are so arranged, that when the free edge of the blank 16 is disengaged it may lie flat against the rear of the panel 10, as indicated in dot-and-dash lines in Figure 4; and when the blank 16 is braced beneath the abutment strip 18, it is thereby flexed into conformity with a conical surface. 45

by forced into conformity with a conical surface. 45
Essentially, it is to be noted that the blank 16 is concave. The conical configuration is preferable in connection with an opening 14 depicting a falling stream of diverging width, but, obviously, the blank 16 may under different circumstances 50 be concaved in various ways.

The front surface of the blank 16 is colored and of high lustre, and the best result is obtained by coating this surface with colored metallic foil. The effect which is produced is unique and 55

striking, because the flexed metallic foil partakes of a variegated sheen and gloss which is remarkably similar to the reflective properties of a stream of actual liquid.

5 In the device illustrated in the drawing, it is preferable to have the blank 16 provided with a front surface of one color and to have the corresponding blank 19 (similarly arranged behind the opening 15) of a different color; although it 10 will be understood that the invention does not require the depiction of two separate streams, nor do the streams necessarily have to be of different colors.

15 The attractive appearance of the device is enhanced further by providing on the panel one or more portions which project across or into the openings. I have illustratively shown portions 20 projecting part-way into the opening 14, and portions 21 similarly projecting into the 20 opening 15. These portions are preferably integral with the panel 16, as will be observed upon viewing Figure 5. Each one of these portions forms part of a depiction, on the front of a panel, of something which is apparently subjected to the action of the flowing stream of liquid. Thus, in the illustrated embodiment, one 25 of the portions 21 is part of a picture of a table 22; and the other portion 21 is part of a picture of another article of furniture 23. Preferably, 30 the projecting portions 21 are colored corresponding to the color of the stream into which they apparently project. The display thus depicts an article or thing which is apparently subjected to the action of the flowing liquid, and in 35 the illustrated device the articles of furniture 22 and 23 are shown as they would appear after being coated with the paint from the can 13.

It will be understood by those skilled in the art that a large variety of different effects may 40 be produced by means of the present invention, and that it is by no means restricted to the depiction of paint.

In general, it will be understood that changes in the details, herein described and illustrated 45 for the purpose of explaining the nature of my invention, may be made by those skilled in the

art without departing from the spirit and scope of the invention as expressed in the appended claims. It is, therefore, intended that these details be interpreted as illustrative, and not in a limiting sense.

5

Having thus described my invention, and illustrated its use, what I claim as new and desire to secure by Letters Patent is—

1. In a display device, a panel depicting the source of a flowing stream of liquid, said panel 10 having an opening with irregularly curved side edges conforming substantially to the contour of said stream, and a concave element behind said opening and having a colored surface of high lustre, said element having rectilinear side edges 15 arranged behind and out of alignment with said curved side edges so as to be concealed by the latter.

2. In a display device, a panel depicting the source of a downwardly widening flowing stream 20 a viscous liquid such as paint, said panel having an opening with irregularly curved side edges conforming substantially to the contour of said stream, and a concave element behind said opening and having a colored surface of high lustre, 25 said element comprising a cardboard blank flexed into conformity with the surface of a cone whose narrower portion is behind the narrower portion of said opening, and said element having rectilinear side edges arranged behind and out of 30 alignment with said curved side edges so as to be concealed by the latter.

3. In a display device, the elements set forth in claim 1, in combination with a panel portion 35 projecting into said opening and hence apparently into the path of said stream, said portion bearing a depiction of something subjected to the action of said stream.

4. In a display device, the elements set forth in claim 2, in combination with a panel portion 40 projecting into said opening and hence apparently into the path of said stream, said portion bearing a depiction of something subjected to the action of said stream.

NATHAN JOSEPH LEIGH. 45
